CLAIM

The ornamental design for an animal dropping clean-up scoop for use with a disposable plastic bag, as shown and described.

DESCRIPTION

FIG. 1 is a front elevational view of an animal dropping clean-up scoop for use with a disposable plastic bag, showing my new design;

FIG. 2 is a bottom end view thereof;

FIG. 3 is a side elevation view thereof;

FIG. 4 is a rear elevation view thereof;

FIG. 5 is a top elevation view thereof; and

FIG. 6 is a perspective view thereof shown with the scoop bag holder separated.

The broken line disclosure of a plastic bag in FIG. 6 is for illustrative purposes only and forms no part of the claimed design.
